UNITED STATES PATENT OFFICE.

EMANUEL MOOR, OF MONT PELERIN, SWITZERLAND.

KEYBOARD FOR KEY INSTRUMENTS.

Application filed November 9, 1920, Serial No. 422,836, and in Switzerland April 9, 1920.

The movements of the hands of pianists, especially for executing certain difficult musical compositions, is very complicated with respect to the numerous and rapid movements which are to be made with both hands in order to reach notes or groups of notes distant from one another by an octave or more. Certain compositions cannot be executed by the average pianist owing to the difficult hand movements necessary to their execution and also because certain chords and tremolo effects in octave are extremely difficult to produce on a piano with the usual key-board.

The object of my invention is to facilitate the execution of all musical compositions and especially of the complicated difficult ones.

The invention consists in certain improvements in connection with duplex keyboard musical instruments as specifically set out in the following description and claims.

The main feature of the present invention embodies a mechanical coupling device which may be put into or out of operation instantaneously during playing at the will of the operator, and which when in operation effects the coupling of single keys of the front keyboard to the movements of two notes an octave apart, whereby actuation of an individual key of this keyboard will sound not only the note corresponding thereto, but also will sound simultaneously a note displaced by an octave from the note first mentioned, the coupling mechanism, however, not interfering with the ability to play each keyboard independently whether the coupler be in operation or out of operation.

A subsidiary feature resides in the application to such an instrument as is indicated above of projections upon the white keys of the front keyboard which materially facilitate simultaneous depressing of keys in both keyboards by means of one hand.

In the accompanying drawings which illustrate a preferred embodiment of a keyboard according to the invention:

Fig. 1 is a plan view partly broken away showing the two banks of keys.

Fig. 2 is a vertical sectional view illustrating connection between the keys of both keyboards and the hammer action movements actuated thereby.

Fig. 3 is a fragmentary side elevation of a form of key which may conveniently be used for one bank of keys.

Referring to the drawing in detail, A designates a bank of keys, the disposition of which is exactly the same as in a usual pianoforte, except that the length of the keys is here a little less than usual. By means of the keys of this bank, the strings of the instrument are normally caused to vibrate as in instruments generally used. The supplementary bank of keys is designated by B; and is supported by a transverse rail *c* lying on the fulcrum pins *d* of the first bank of keys A, the rail being also provided with fulcrum pins for the keys of the bank D. The keys of the bank B have the usual form as shown in Fig. 1 and they are connected along oblique lines as indicated at *b'* in Fig. 1 with the striking mechanisms (levers, hammers, damper) of strings an octave higher than the aligning keys of the bank A. The keys of both banks are normally completely independent of one another; each key corresponds to one note only, but permitting such note to be struck from two different points along the length of the keyboard, that is to say by means of two keys one located in each bank and distant from one another by an octave.

By means of this arrangement, it is possible to strike chords, at intervals for instance of an octave, by a simple movement of the hand forward and backward. Musical compositions ordinarily requiring crossing of the arms may be executed without the hands leaving the key-board, thus reducing the effort necessary for the execution of the composition on the usual pianoforte. This result may be obtained without necessitating further study in the art of piano playing and without any modification of existing music whatever.

In order to facilitate play rendered difficult by the position of the black keys of the front bank between the two banks of white keys, portions of the white keys of the front bank are raised to the height of or above the black keys in *a* as indicated at *a'*, but this only on a certain part of their length. This increase in height could also be made by means of projections of various types provided on each white key between the black keys of the front bank. It is possible to have white keys with a longitudinal section as shown in Fig. 3, that is to say with the raised portions of the keys gradually increasing to the height of the black keys.

In order to give full advantage of a key-

board constructed in accordance with the invention, the instrument is provided with a device actuated by means of a pedal or the like (not shown), which allows the coupling 5 at will, from octave to octave, of all notes of the front or lower range. This coupling device is represented diagrammatically by dot and dash lines in Figure 1, and is shown in detail in Figure 2. As will be clear from 10 an inspection of Figure 2, if, after having elevated the part *j* about its fixed pivot *m* by means of a pedal (not shown), a key of the front bank *A* be depressed, then that key—in addition to operating its own hammer movement in the ordinary manner—will bear upon the tappet lever *g* and the seesaw lever *l* will be rocked about its fulcrum *t*, so as to raise the tappet *n*. This in turn 15 rocks the lever *o* pivoted at *p*, which by means of the link *q* in its turn rocks the escapement lever *P* pivoted at *s*, thus operating in well known manner the hammer of a note situated an octave above (in pitch); it being borne in mind that all the seesaw 20 levers *l* lie obliquely across the fulcrum rail *t* so as to couple individual keys with hammer movements which are displaced by an octave therefrom.

As regards the keys *B* in the upper or 30 rear keyboard of Figure 2, it is to be understood that these keys are permanently cranked or staggered, as represented in Figure 1 in plan, so that individual keys do not operate the movements which lie immediately behind them, but operate movements 35 displaced by an octave.

The keyboard whose keys are permanently displaced in this manner is shown disposed 40 behind and above the keyboard which is provided with the permissive coupling device, but the relative positions of the keyboards may be transposed if desired.

I claim:—

1. A musical instrument of the keyboard 45 type having two keyboards lying one behind the other and independently playable at all times, permanent motion-transmitting members for the individual keys of one keyboard adapted to transmit obliquely movements of

such keys to corresponding individual hammer movements of a musical instrument which are displaced by an octave therefrom, and an octave coupling device for the other of said keyboards which may be put into or out of operation at will and which when in 55 operation enables each individual key in that keyboard to sound a chord constituted by the corresponding note and a note displaced an octave therefrom.

2. A musical instrument of the keyboard 60 type having two keyboards lying one behind the other and independently playable at all times, permanent motion-transmitting members for the individual keys of one keyboard adapted to transmit obliquely movements of 65 such keys to corresponding individual hammer movements of a musical instrument which are displaced by an octave therefrom, an octave coupling device for the other of said keyboards which may be put into or out of operation at will and projections on the white keys of the front keyboard, the upper surface of which is raised at an approximately similar level to that of the 70 upper surface of the black keys.

3. A musical instrument of the keyboard 75 type having two keyboards lying one behind the other independently playable at all times, cranked seesaw keys for the individual keys of the rear keyboard, the rear end 80 of each key being adapted to coact with a hammer movement of a musical instrument displaced an octave from the note lying directly behind the front end of the key, and an octave coupling device for the keys of 85 the front keyboard capable of being brought into or out of operation at will and comprising a seesaw lever pivoted upon a movable fulcrum rail, said seesaw lever when operated upon coacting at its front end with a 90 front key and coacting at its rear end with a hammer movement which is displaced an octave from the note lying directly behind said key.

In testimony whereof he affixes his signature. 95

EMANUEL MOOR.
